E. E. DAVIS

COLUMN FORM CLAMP

Filed Feb. 15, 1926

UNITED STATES PATENT OFFICE.

EDWARD E. DAVIS, OF CHICAGO, ILLINOIS.

COLUMN-FORM CLAMP.

Application filed February 15, 1926. Serial No. 88,321.

This invention relates to improvements in column form clamps, and more especially to such a clamp adapted for use in holding the boards or forms used in making concrete or similar columns or posts.

My improved clamp is strong and durable yet cheap to manufacture; and it will be found very efficient and simple in use.

The various bars forming the complete clamp are also interchangeable so that no fitting or difficult selection of parts is required in the use of the device.

By the use of my invention, also, I am able to provide a clamp capable of very fine and accurate adjustment.

Other features and advantages of my invention will appear more fully as I proceed with my specification.

In that form of device embodying the features of my invention, shown in the accompanying drawings, Figure 1 is a plan sectional view through a column form showing my improved clamp applied thereto, Fig. 2 is a view of the clamp in side elevation, Fig. 3 is an enlarged view in top plan of a part of the clamp, and Fig. 4 is a detailed view showing the spacing block at the end of one of the clamp bars.

As shown in the drawings, 10 indicates a wooden form for the concrete column of any desired construction, and here shown as composed of four separate boards placed together. The concrete is poured into the form in the usual manner and for the purpose of clamping and holding the boards forming the form securely in place during the pouring and setting of the concrete I provide clamps at suitable intervals.

I will now describe more in detail one of the clamps. As shown, the clamp consists of four separate bars indicated in general by 11, 11. Since each of these bars is the same, I will describe in detail but one.

The bar 11 is provided with a series of longitudinal slots 12, 12, at one end arranged at suitable intervals. The other end of the bar is provided with a loop made in any suitable manner and here shown formed by means of the extension pieces 13, 13 riveted to the end of the bar by the two rivets 14, 14. It will be seen that the extension pieces 13, 13 are separated by the width of the bar 11 to form the open loop 15. The outer ends of the extension pieces 13, 13 are joined by means of a rivet 16 which carries piv-

oted upon it between the extension pieces 13, 13 a square cam or spacing block 17 to be described more in detail hereinafter.

In the use of the device, the slotted end of one of the bars is inserted in the open loop 15 of the adjacent bar. Each bar is provided with a wedge 18 to fit into any one of the slots 12, one edge of the wedge engaging the end wall of the slot into which it is inserted and the other bearing on the outer edges of the extension pieces 13, 13 and operating to force the bars inwardly against the form. By providing a series of these slots 12, 12 in each bar, it will be seen that various adjustments are permitted.

Although the spacing of the slots 12, 12 permits certain adjustments, it will be seen that such adjustments cannot be finer than the distance by which the slots are separated. In order to permit finer adjustments than these I provide a cam or spacing block 17 at the end of each bar pivoted on the rivet 16 joining the ends of the extension pieces 13, 13. It will be seen by reference to Fig. 4 that the block 17 is free to turn on the rivet 16 but that this rivet is not placed in the center of the block. It is eccentrically arranged so that by turning the block 17 into the four positions indicated by 17, 17^a, 17^b and 17^c, the bearing edge against which the adjacent bar 11 rests, and as indicated in Fig. 4 by 117, 117^a, 117^b, and 117^c respectively, will vary in its distance from the end of the bar. Preferably, the cam or spacing block 17 is made of such a size and the hole in it through which the bolt 16 passes is so located that turning of this block will give four adjustments, the aggregate distance of which is substantially the same as the distance between two adjacent slots 12. By this arrangement it will be seen that it is possible to obtain four additional adjustments or spacings between any two of the slots 12. This is accomplished, as stated, by turning the block 17 into one of its four positions.

While I have shown and described certain embodiments of my invention, it is to be understood that it is capable of many modifications. Changes, therefore, in the construction and arrangement may be made without departing from the spirit and scope of the invention as disclosed in the appended claims, in which it is my intention to claim all novelty inherent in my invention as

broadly as possible in view of the prior art.

What I claim as new, and desire to secure by Letters Patent, is:

1. A form clamp comprising; a plurality of bars, each bar having a series of slots at intervals therein at one end and an elongated loop at the other end, said loop adapted to receive the slotted end of an adjacent bar; a wedge for each bar adapted to fit within a slot in the end of a bar projecting beyond the loop with one edge bearing against the outer end wall of the slot and its opposite edge bearing against the outer edge of said loop; and adjustable means for holding the end of a bar within a loop at different distances from the end of said loop, said means comprising a spacing block provided with a plurality of differently spaced abutment faces.
2. A form clamp comprising; a plurality of bars, each bar having a series of slots at intervals therein at one end and an elongated loop at the other end, said loop adapted to receive the slotted end of an adjacent bar; a wedge for each bar adapted to fit within a slot in the end of a bar projecting beyond the loop with one edge bearing against the outer end wall of the slot and its opposite edge bearing against the outer edge

of said loop; and adjustable means for holding the end of a bar within a loop at different distances from the end of said loop, said means comprising a spacing block provided with a plurality of differently spaced abutment faces, any one of said faces adapted to be placed into operative position by movement of the block.

3. A form clamp comprising; a plurality of bars, each bar having a series of slots at intervals therein at one end and an elongated loop at the other end, said loop adapted to receive the slotted end of an adjacent bar; a wedge for each bar adapted to fit within a slot in the end of a bar projecting beyond the loop with one edge bearing against the outer end wall of the slot and its opposite edge bearing against the outer edge of said loop; and adjustable means for holding the end of a bar within a loop at different distances from the end of said loop, said means comprising a pivoted spacing block provided with a plurality of differently spaced abutment faces, any one of said faces adapted to be placed into operative position by rotation of the block.

In testimony whereof, I have hereunto set my hand this 13th day of February, 1926.

EDWARD E. DAVIS.
